STERILIZING APPARATUS

James E. Myers, Whitefish Bay, and William F. Simonsen, Milwaukee, Wis.

Application February 3, 1934, Serial No. 709,588

5 Claims. (Cl. 99—18)

The present invention relates in general to improvements in the construction and operation of sterilizing apparatus for toilet articles such as tooth brushes or the like.

Generally defined, an object of the invention is to provide an improved dry-heat sterilizer which is simple in construction and highly effective in use.

While it has heretofore been proposed as shown and described in United States Patent No. 1,873,627, granted August 23, 1932, to sterilize individual tooth brushes or the like by placing the object within a heat conducting sheath formed of wire gauze or screening so as to permit dry-heat sterilization while preventing direct access of the flame to the object, this prior method does not permit effective utilization of the available heat. The use of gauze or screening is, however, very effective in preventing direct access of the flame to the objects, but if the objects are permitted to contact directly with the heated sheath, they are apt to become scorched or otherwise damaged.

It is therefore a more specific object of the present invention to provide improved apparatus for utilizing the prior method of dry-sterilization to some extent, but which will insure most efficient utilization of the available heat while at the same time preventing possible damage to the objects being treated.

Another specific object of the invention is to provide an improved dry-heat sterilizer wherein the applied heat is most effectively distributed so as to insure uniform heat treatment of all portions of the objects, and wherein one or more of the objects may be simultaneously sterilized.

A further specific object of the invention is to provide an improved tooth brush sterilizer or the like, for heat treating elongated objects by causing the heat to travel through elongated channels within which the brushes are located, the channels preferably being disposed vertically so as to secure the benefit of natural circulation of the heated air which is utilized as a sterilizing medium.

Still another specific object of the invention is to provide an improved dry-heat sterilizing casing which may be readily manufactured, and improved means for detachably suspending the casing from a wall or other support without marring the same.

An additional specific object of the invention is to provide a sterilizer for tooth brushes or other toilet articles, which may be conveniently assembled or dismantled for cleaning purposes, and which may be operated without danger.

A further specific object of the invention is to provide improved dry-heat sterilizing apparatus which is compact and durable in construction, which may be manufactured and sold at minimum cost, and which may be utilized for diverse sterilizing purposes by a novice.

These and other objects and advantages will be apparent from the following detailed description.

A clear conception of the various improved features, and of the mode of constructing and of utilizing tooth brush sterilizers built in accordance with the present invention, may be had by referring to the drawing accompanying and forming a part of this specification in which like reference characters designate the same or similar parts in the various views:

Fig. 1 is a part sectional front elevation of an improved multiple, dry-heat, tooth brush sterilizer;

Fig. 2 is a central vertical section through the sterilizer of Fig. 1, taken along the line 2—2;

Fig. 3 is a top view of the sterilizer, a portion of the upper rubber seal having been broken away so as to more clearly show the cover structure;

Fig. 4 is a transverse horizontal section through the sterilizer, taken along the line 4—4 of Fig. 1; and

Fig. 5 is a top view of the flame baffle and heat distributor.

While the invention has been shown and described herein as being specifically applied to a dry-heat sterilizer for tooth brushes, it is not intended to thereby limit the invention since some of the novel features are obviously more generally applicable to other types of sterilizing equipment.

Referring to the drawing, the dry-heat sterilizer shown therein by way of illustration, comprises in general a main casing 8 preferably constructed of a single sheet of metal and having therein a partition insert 9 forming four upright passages or compartments 10; a multiple heat permeable screen 11 confined within the casing 8 and spanning the corresponding lower ends of the compartments 10; a heat distributor 12 carried by the casing 8 beneath the screen 11; a cover 13 hingedly connected to the insert 9 and forming a closure for the upper corresponding ends of the compartments 10; and means such as suction cups 14, 15 for detachably suspending the sterilizer from a wall or the like.

As above indicated, the main casing 8 may be formed of a single piece of sheet metal, with the aid of punches and dies, and the lower part of

this casing 8 has angular wall portions 16 formed integral with the casing side walls and forming a direct support for the screen 11 and distributor 12, between the front and rear walls of the main 5 casing, as shown in Figs. 1 and 2. The partition insert 9 may likewise be constructed of a single piece of sheet metal by folding the partition walls 17 as shown in Fig. 4, and the lower ends of these walls normally rest upon the screen 11 which in 10 turn rests upon the upper extremities of the wall portions 16. Each of the side walls and partition walls 17 of the insert 9, is provided at its lower end with an integral lateral extension 18 as shown in Figs. 1 and 4, for supporting an object 15 such as a tooth brush 19 confined within the adjacent flue 16, above and out of contact with the screen 11 in the manner illustrated in Fig. 1, and the cover 13 which may also be formed of sheet metal is pivotally attached to the upper extremities 20 of the side walls of the insert 9 and has slots 20 therein for receiving the tooth brush handles while the brushes are being sterilized within the compartments 10. A flexible rubber seal 21 supported on top of the cover 13, has slits 22 for 25 receiving the tooth brush handles, and serves to prevent undesirable escape of heat from the compartments 10 past these handles when the cover is closed.

The distributor 12 is shown in detail in Figs. 1, 30 2 and 5, and may be formed either of sheet metal or of screening, and has cut-outs 23 at the sides and ends thereof, as indicated in Fig. 5. The distributor 12 has suspension hooks 24 at the corners thereof, and is moreover of angular formation 35 so as to direct the flame applied by a lamp 25 or otherwise, toward the front and rear cut-outs 23 and along the upper wall portions 16 into all portions of the heat distributing zone 26 located between the distributor 12 and the screen 11. The screen 11 is also preferably formed of several superimposed layers of screening having the meshes staggered so as to further enhance the uniform delivery of heat to the compartments 10; and it will be noted that the portions 40 of the extensions 18 which coact directly with the screen 11, are cut away so as to cause minimum obstruction to the flow of heating air. It will be apparent, that with this assemblage of elements, the screen 11 will be protected from direct contact 45 with the flame which impinges only against the distributor 12, and that uniform distribution of the heat is insured.

The suction cups 14, 15 may be of the ordinary rubber type having threaded integral studs 27 55 adapted to engage threaded openings in the rear wall of the casing 8 as shown in Fig. 2. The lower suction cup 15 is preferably located as far as possible away from the heating flame, as shown, and the rubber of these cups will prevent 60 accidental overheating of the wall to which the sterilizer is attached, both because of the insulating quality of the rubber and because of the spacing afforded by the cups. The rear wall of the main casing 8, may, however, be provided with a 65 suspension opening 28 in addition to the cups 14, 15 for permitting ordinary suspension of the device in case the cups become ineffective.

During normal use of the improved sterilizer, 70 the device is suspended from a wall in an obvious manner with the aid of suction cups 14, 15, and the tooth brushes 19 are inserted in the compartments 10 as indicated in Fig. 1, the cover 13 being closed and the seal 21 serving to effectively prevent undesirable escape of heated gases from the 75 top of the sterilizer. A lamp 25 may then be

applied as shown, and as the flame strikes the deflector 12 it is caused to spread through the distributing zone 26, whereupon the heated gases permeate through the screen 11 and into the compartments 10. By virtue of the formation and location of the distributor 12, the heating gases are uniformly distributed within the zone 26, and by staggering the meshes of the screening constituting the screen 11, the heated gases are furthermore uniformly distributed through 10 the sterilizing compartments 10. While the distributor 12 may become relatively hot, and the screen 11 may also become rather highly heated depending upon the period for which sterilization is being effected, the extensions 18 upon 15 which the bristles of the brushes 19 rest, do not become sufficiently heated to damage the brushes. After sterilization of the brushes 19 has been effected, they may be readily removed by merely swinging the cover 13 rearwardly whereupon the 20 handles of the brushes will pass through the slits 22 in the seal 21.

It will also be apparent that the construction, 25 assemblage and dismantling of the improved sterilizer may be conveniently effected due to the formation of the main casing 8 of sheet metal, and also due to the mode of associating the other elements with the main casing. The insert 9 together with the cover 13 may be freely upwardly removed from within the main casing 8, 30 and thereafter the screen 11 and distributor 12 may likewise be freely withdrawn. This feature is of importance since it permits convenient access to all portions of the sterilizer for cleaning, and when the insert 9 and cover 13 have been removed, the space above the screen 11 may be 35 utilized for sterilizing larger objects than the tooth brushes 19. The studs 27 of the suction cups 14, 15 permit convenient attachment of these cups to the main casing, or removal therefrom, and these cups additionally serve to prevent overheating of the wall to which the sterilizer is attached. The entire device may be appropriately decorated to provide a highly finished appearance, and the distributor 12 which is subjected to the intense heat by virtue of its direct 40 contact with the flame, may be renewed when necessary without necessity of renewing other parts of the apparatus. If desired, the distributor 12 may be perforated or formed of screening 45 instead of sheet metal, and the rubber seal 21 may be disposed beneath the cover 13 as an alternative to the disposition thereof as shown. It will be apparent, that even if the distributor 12 is entirely omitted, the screen 11 will permit 50 propagation of the heat to the compartments 10, while preventing the flame from entering these compartments and thereby injuring the bristles of the brushes 19.

It should be understood that it is not desired 55 to limit the invention to the exact details of construction and to the precise mode of use herein shown and described, for various modifications within the scope of the claims may occur to persons skilled in the art.

It is claimed and desired to secure by Letters Patent:

1. A dry-heat sterilizer comprising, a main casing having a heat distributing chamber in the lower portion thereof and a series of segregated 70 compartments extending upwardly from said chamber, a screen interposed between the top of said chamber and the lower ends of said compartments, a baffle plate at the bottom of said chamber spaced from the side walls thereof, 75

means for applying heat to said chamber centrally beneath said plate and remote from said screen, and a removable closure for the upper ends of said compartments.

5. 2. A dry-heat sterilizer comprising, a main casing having a heat distributing chamber in the lower portion thereof, a series of partitions forming segregated compartments within said casing extending upwardly from said chamber, a screen 10 interposed between said chamber and said partitions, a baffle plate in the lower end of said chamber spaced from the side walls thereof, means for applying heat to said screen from beneath said plate and through said chamber, and a removable closure for the upper ends of said compartments including a flexible heat confining seal.

15. 3. A dry-heat sterilizer comprising, a main casing having an upwardly expanding heat distributing chamber in the lower portion thereof, a series of removable partitions forming segregated compartments within said casing above said chamber, a screen separating said chamber from said compartments, a central baffle plate at the lower constricted end of said chamber spaced 20 from the side walls thereof, means for applying heat to the lower end of said chamber beneath said central baffle and remote from said screen,

and a removable closure for the ends of said compartments remote from said screen.

4. A dry-heat sterilizer comprising, a main casing having a lower heat distributing chamber and a series of segregated compartments extending 5 upwardly from said chamber, a screen interposed between the top of said chamber and the lower ends of said compartments, a baffle plate at the bottom of said chamber spaced from the side walls thereof, and means for applying heat to 10 said chamber around the edges of said plate remote from said screen.

5. A dry-heat sterilizer comprising, a main casing having a lower heat distributing chamber and a series of segregated compartments extend- 15 upwardly from said chamber, the lower end of said chamber being restricted and the upper end being materially larger in area than said lower end, a screen interposed between said upper chamber end and the lower ends of said com- 20 parts, a baffle plate disposed within the restricted lower end of said chamber, and means for applying heat to said chamber from beneath said baffle plate and around the peripheral edges thereof.
